UNITED STATES PATENT OFFICE.

JESSE TEMPLE CURTIS, OF BEMENT, ILLINOIS.

EXPLOSIVE-ENGINE.

1,141,443.

Specification of Letters Patent. Patented June 1, 1915.

Application filed August 20, 1914. Serial No. 857,657.

To all whom it may concern:

Be it known that I, JESSE T. CURTIS, a citizen of the United States, residing at Bement, in the county of Piatt and State of Illinois, have invented a new and useful Explosive-Engine; and I do hereby declare the following to be a full, clear, and exact description of the invention, such as will enable others skilled in the art to which it appertains to make and use the same.

This invention relates to the art of engines, and particularly to internal combustion engines, and as an object of the invention it is the aim to provide a simple, efficient and practical motor of this nature, in which the intake and the exhaust are positive in action, and in which the noise and friction of the moving parts are reduced to a minimum.

Another object of the invention is to provide an engine of this nature, which may be manufactured cheaply, and the cost of repairing reduced to a minimum.

Another object of the invention is the provision of the main or dominant explosive chamber, in which the main piston is operable, and the auxiliary chamber in which the auxiliary piston intake controlling valve operates, which controls the intake of the charge and the exhaust of the utilized gases, both pistons at the same time constituting power developing elements, for imparting motion to the usual crank shaft of the crank casing, this being the design of the invention, that the auxiliary piston makes one-half as many strokes as the main piston.

In practical fields the details of construction may necessitate alterations, falling within the scope of what is claimed.

The invention comprises further features and combination of parts, as hereinafter set forth, shown in the drawings and claimed.

In the drawings:—Figure 1 is a vertical sectional view through the casing of the engine, showing the relative positions of the main and auxiliary pistons at the time of the intake of a charge. Fig. 2 is a similar view showing the relative positions of the main and auxiliary pistons at the time of compressing the charge. Fig. 3 is a view similar to Figs. 1 and 2 showing the positions of the main and auxiliary pistons after the charge has been fired. Fig. 4 is a sectional view similar to Figs. 1, 2, and 3 showing

ing the main piston in the act of cleaning 55 the dominant chamber of the utilized gases, which pass out through the exhaust port and after the dominant chamber has been cleaned the main piston moves downwardly, and as it reaches the limit of its downward 60 stroke at this period, the auxiliary piston reaches the limit of its upward stroke, in view of which it will be seen that the position of the pistons will again assume positions as shown in Fig. 1 in order that 65 another charge may be taken into the dominant chamber so as to be compressed and fired. Fig. 5 is a transverse sectional view on line 5—5 of Fig. 1.

Referring more particularly to the drawings, 1 designates the usual crank casing, in which the main crank shaft 2 is mounted in bearings, which crank shaft may have two fly wheels, in order to lend momentum to the shaft, only one fly wheel being illustrated, as designated at 3. Above the crank casing the main piston casing 4 is provided having the dominant explosive chamber 5 and the auxiliary piston valve chamber 6, in communication with the chamber 5 by 80 virtue of the port 7. Surrounding the casing 4 is the usual water jacket 8, thereby providing the water space 9 for keeping the dominant and auxiliary chambers 5 and 6 cool. The usual sparking plug 10 is provided having the sparking terminals 11. Mounted to reciprocate in the chamber 5 is the main or dominant piston 12 provided with the usual packing rings 13. Pivoted upon the pin 14 of the piston 12 is the usual pitman rod 15, which in turn is pivoted at 16 to the crank 17 of the crank shaft 2. Mounted to reciprocate in the auxiliary chamber 6 is the auxiliary piston valve 18 having the usual packing 19, and provided adjacent the lower portion or end thereof with a reduced portion 20, forming an annular channel 21. Connected pivotally at 22 to the lower end of the piston valve 18 is a pitman rod 23, which in turn has connections 24, 25, 26 and 27 with the shaft 2, whereby the auxiliary piston valve may make half as many strokes as the dominant piston 12, and move at the same relative speed as the piston 12. The casing 4 is provided with the intake ports 28 and 29 and the exhaust port 30.

To lubricate the moving parts the crank

casing is supplied with lubricant, which lubricates the shaft 2 and the crank and the connections between the shaft 2 and the pitman 23, and as these parts are in the act 5 of moving the lubricant is splashed upon the lower portions of the pistons, thereby lubricating them.

The port 7 remains opened all the time. The port 29 is so arranged in the wall 10 between the chamber 6 and the chamber 5, that it is opened following the suction stroke of the piston 12, and is covered or closed by the valve piston 18 following the explosion stroke. The particular advantage 15 in this two chamber, two piston, four cycle engine is the simplicity of construction, and the placing of the intake port near the lower end of the cylinder permits the control of both the intake and the exhaust 20 ports with an auxiliary piston valve working in conjunction with the main piston, which reduces the wear upon the moving parts to a minimum. The use of the two simple pistons in this form of engine together 25 with the usual packing rings, permits the sealing of the main and auxiliary chambers against loss of compression and explosion, which has been proven to be the most reliable way of obtaining perfect compression and retention of the explosive 30 forces.

Operation: Referring to Fig. 1 it will be seen that a charge is being sucked in through the intake ports 28 and 29, through 35 the annular channel 21. The dominant piston 12 then makes its upward stroke, the exhaust port 30 being closed, thereby compressing the charge. However, before the charge is sucked into the chamber 5 the piston 12 uncovers the port 29. As the piston 40 12 moves toward the port 29, a suction is created, and when the piston 12 reaches the port 29, the suction is so great at the time of opening the ports 28 and 29 that a sufficient charge is immediately drawn or 45 sucked into the chamber 5, by way of the ports 28 and 29 and the channel 21. As before stated, the piston 12 then continues upwardly and compresses said charge. The piston 18 remains practically in the position 50 shown in Fig. 2, until the charge is compressed. Immediately following the compression of the charge the firing takes place, and the expansion of the gases im- 55 parts downward movements to the dominant and auxiliary pistons, and as the dominant piston 12 reaches the limit of its downward stroke, the auxiliary or supplemental piston 18 uncovers the exhaust port 30, and re- 60 mains uncovered until the dominant piston 12 makes another upward stroke, thereby scavenging the chamber 5 and forcing the utilized gases out through the exhaust port, and as the dominant piston 12 again reaches 65 the limit of its upward stroke, the exhaust

port is closed by the auxiliary or supplemental piston valve 18. These cycles of operations repeatedly continue, thereby imparting movement to the shaft 2, which may be geared in any suitable manner (not 70 shown) to machinery to be operated.

The invention having been set forth, what is claimed as new and useful is:—

1. In an internal combustion engine, a casing having dominant and auxiliary 75 chambers, pistons operable therein, one being a dominant piston and the other an auxiliary piston, an exhaust port in the auxiliary chamber, a port of communication between the upper end of the dominant and auxiliary chambers offset above said exhaust port and being open during the working strokes of said pistons, a port of communication between the lower portions of the dominant and auxiliary chambers, an intake 80 port in the lower portion of the auxiliary chamber offset below the port of communication between the lower end of the auxiliary and dominant chambers, said auxiliary piston having means forming communications between the intake port and the explosion chamber through the lower port of communication between the dominant or explosion chamber and the auxiliary chamber when the dominant piston is at the limit of 85 its downward stroke, and means of connection between the dominant and auxiliary pistons whereby the auxiliary piston is held substantially at its limit of its upward stroke with the exhaust port closed while the dominant piston is making its compression stroke, the firing of the charge immediately following the compression stroke thereby forcing both pistons downwardly.

2. In an internal combustion engine, a 105 casing having dominant and auxiliary chambers, pistons operable therein, one being a dominant piston and the other an auxiliary piston, an exhaust port in the auxiliary chamber, a port of communication between 110 the upper end of the dominant and auxiliary chambers offset above said exhaust port and being open during the working strokes of said pistons, a port of communication between the lower portions of the dominant and auxiliary chambers, an intake port in the lower portion of the auxiliary chamber offset below the port of communication between the lower end of the auxiliary and dominant chambers, said auxiliary piston having an annular channel adjacent its 115 lower portion forming communication between the intake port and the explosion chamber through the port of communication between the lower portions of the dominant or explosion and auxiliary chambers when the dominant piston is at the limit of its downward stroke, and means of connection between the dominant and auxiliary pistons whereby the auxiliary piston is held 120 125 130 135 140

substantially at its limit of its upward stroke with the exhaust port closed while the dominant piston is making its compression stroke, the firing of the charge immediately following the compression stroke thereby forcing both pistons downwardly.

5 In testimony whereof I have signed my

name to this specification in the presence of two subscribing witnesses.

JESSE TEMPLE CURTIS.
